Term of patent 14 years

(Cl. D90—1)

FIG. 1.

FIG. 2.

FIG. 3.

FIG. 4.

FIG. 5.

FIG. 1 is an isometric view of a combination identification and turn signal unit for bicycles showing my new design.

FIG. 2 is a left side elevational view thereof, with parts broken away for convenience of illustration.

FIG. 3 is a top plan view thereof, with parts broken away.

FIG. 4 is a front elevational view thereof.

FIG. 5 is a rear elevational view thereof.

The right side elevational view is symmetrically identical to FIG. 2 and the bottom plan view is identical to FIG. 3.

The numerals shown in broken lines are included only for illustrative purposes.

I claim:

The ornamental design for a combination identification and turn signal unit for bicycles, substantially as shown and described.
